UNITED STATES PATENT OFFICE

2,418,862

CONVERTIBLE LADDER

James S. Anderson, Vancouver, British Columbia, Canada

Application February 13, 1945, Serial No. 577,612

2 Claims. (Cl. 228-2)

1

The present invention relates to new and useful improvements in ladders and more particularly to a convertible ladder adapted for use for different purposes, such as a straight ladder, step ladder, as a scaffolding support and for various other purposes where a ladder is desired.

An important object of the invention is to provide a convertible ladder of this character in which the parts may be folded into compact form.

A still further object is to provide a convertible ladder of simple and practical construction, which is strong and durable, relatively inexpensive to manufacture, which may be easily and quickly arranged in its several forms for different purposes and which otherwise is well adapted for the purposes for which the same is intended.

Other objects and advantages reside in the details of construction and operation as more fully hereinafter described and claimed, reference being had in the accompanying drawings forming part hereof, wherein like numerals refer to like parts throughout, and in which:

Figure 1 is a front elevational view showing the device arranged as a straight ladder.

Figure 2 is a side elevational view thereof.

Figure 3 is a side elevational view of the ladder arranged for use as a step ladder.

Figure 4 is a front elevational view showing the device as a scaffolding support.

Figure 4a is a side elevational view thereof.

Figure 5 is a fragmentary top plan view of one of the rungs of the ladder extension showing the bracket provided for accommodating the connecting bar between the upper and lower sections of the ladder.

Figure 6 is a side elevational view thereof.

Figure 7 is a sectional view taken substantially on a line 7—7 of Figure 6.

Figure 8 is a side elevational view of a modified scaffolding support.

Figure 9 is an enlarged side elevational view of the brace for the scaffolding support.

Figure 10 is an edge elevational view with parts broken away and shown in section.

Figure 11 is a transverse sectional view taken substantially on a line 11—11 of Figure 9.

Figure 12 is an enlarged detail in elevation of one of the folding rungs for use with a straight ladder.

Figure 13 is an enlarged edge elevational view of one of the braces shown in Figure 4a.

Figure 14 is a side elevational view thereof.

Figure 15 is an enlarged side elevational view

2

of one of the folding rungs and with parts broken away and shown in section.

Figure 16 is a top plan view thereof.

Figure 17 is a detail sectional view, taken on the line 17—17 of Figure 15.

Referring now to the drawings in detail and first with respect to the form of the invention illustrated in Figures 1 and 2 of the drawings, the numeral 5 designates a lower ladder section 10 having a pair of upwardly converging side rails 6 connected by the rungs 7.

As illustrated more clearly in Figure 12 of the drawings, the upper ends of the side rails 6 are provided with metallic cover plates 8 to protect

15 the upper ends of the rails and to reinforce the same and between the plates 8 is positioned one end of a pole 9 pivoted on a pin 10 inserted transversely through the plates as well as through

19 the upper ends of the rails 6. The other end of the pole 9 extends between a pair of converging rails 11 forming a ladder extension in which the rails are connected by rungs 12, the pole 9 being pivoted on a pin 13 extending transversely at

23 the converging ends of the rails 11.

25 One of the rungs 12 is separated centrally of its length as indicated in Figures 5 to 7, inclusive, the separated meeting ends of the rungs being connected by a substantially U-shaped bracket 14 having its ends bent outwardly as shown at 15

29 and secured to the sections of the rungs by means of bolts or the like 16. The pole 9 passes between the separated ends of the rung for seating in the bracket 14 to brace the pole and the extension when the latter are arranged in an upright position

33 as indicated in Figure 2 of the drawings. That is to say, in the opened and longitudinally aligned straight ladder condition of the foldable sections as shown in Figures 1 and 2, the pole member 9 has its upper end portion seated in the

37 U-shaped bracket 14, said pole end portion being preferably secured rigidly to said bracket 14 by a removable bolt, not shown but obviously passable through a transverse bore in the pole member

41 and aligned apertures provided in the opposite side walls of the bracket, as indicated in dotted lines in Figures 5 and 6 and in a full circular line in Figure 7. This gives ample rigidity to the ladder and prevents folding of the adjoining sections

45 on the hinge joint 13. So, too, while sufficient rigidity may be given to the ladder by merely tightening the pivots 10 and 13, it is obvious that

further dependable rigidity is afforded by the aforesaid provision of the interfitting and attaching arrangements of the bracket 14 to the adjacent end portion of the pole member 9 and adja-

71

75

cent the pivot 13. It is further obvious that the same bracket provision and arrangement may be made to supplement the tightened pivot 10. Rigidity of the straight ladder arrangement is further augmented by the provisions and arrangements to be now described.

The outer edges of the plates 8 are rolled to form bearings 17 in which a bolt 18 is journaled, the bolt being removably secured transversely of a folding rung 19 of tubular construction and hollow at its outer end to form a chamber 20 within which a pin 21 is slidably mounted and projected outwardly by means of a coil spring 22 positioned within the chamber inwardly of the pin (see Fig. 15).

The outer end of the rung 19 is formed with a hook 23 adapted to receive a rope or cable 24 clamped in position within the hook by means of the outwardly projecting end of the pin 21. The rung 19 is formed with a longitudinally extending slot 25 through which a button 26 carried by the pin 21 projects to provide for the manual retraction of the pin in order to release the rope or cable 24, when desired.

The ends of the rope or cable 24 are attached to projections 27 on the ends of the rungs 7 as well as to similar projections 28 on one of the rungs 12 and the pole 9 is provided at opposite sides with folding rungs 29' similar to the rungs 19 and likewise embodying means for gripping the ropes or cables 24 to provide an intermediate ladder section extending between the lower ladder section 5 and the upper ladder section 11 and thus provide a substantially straight rigid ladder. Obviously, instead of using originally flexible ropes or cables as the members 24, the same may be rigid rods, bars or strips of metal or wood. If the latter are used it is not necessary to apply excess longitudinal tension to the members as is necessary with ropes or cables to give the required rigidity to the structure.

The cables or ropes 24 may be detached from the folding rungs 19 and the folding rungs moved into folded position or removed by removing the bolt 18 from the bearing 17 and the pole 9 and upper extension 11 swung into a position to form a step ladder as shown in Figure 3 of the drawings.

For this purpose the lower and upper sections 5 and 11 are secured in spaced apart relation by means of a foldable sectional brace indicated generally at 29 and illustrated in detail in Figures 9 to 11, inclusive.

The brace 29 comprises a pair of plates 30 and 31 pivotally connected to each other at one end by means of a pin 32, the plates being slidably mounted in channel-shaped extensions 33 and 34, respectively. The outer ends of the extensions are formed with openings 35 adapted for pivotally attaching to one of the rails of the upper and lower ladder sections.

The plate 30 and extension 33 are formed with longitudinally extending slots 36 through which a bolt and wing nut 37 are inserted for securing the extension 33 in longitudinally adjusted position on the plate 30 and the plate 31 and extension 34 are formed with similar longitudinally extending slots 38 through which a bolt and wing nut 39 are secured for likewise securing the extension 34 in longitudinally adjusted position.

The ladder may likewise be arranged to provide a support for one end of scaffolding as illustrated in Figure 8 of the drawings by positioning the pole 9 horizontally and supporting the lower end of the ladder extension 11 on a step 40 so that planks 41 for the scaffolding may be supported on the

horizontally arranged pole 9. In order to support the planks 41 two of the ladder units are provided, one at each end of the planks.

Inwardly disposed end of the pole 9 may be provided with a resilient pad 42 to prevent injury to the wall 43 of a building while the scaffolding is in use.

The ladder may also be converted into a modified form of scaffolding support as illustrated in Figures 4 and 4a of the drawings and for this purpose the ladder extensions 11 are removed and the pole 9 supported in a horizontal position on the upper end of the lower ladder section 5 by means of one or more braces 44. This form of the brace comprises upper and lower plates 45 and 46 having their ends arranged in overlapping relation, the plate 45 being secured to one of the rails 11 of the upper ladder section by means of a bolt 47 and the braces 44 are secured to the respective side rails of the upper ladder section 11 by means of a pair of clamping plates 48 extending horizontally thereof.

The lower end of the plate 45 is provided with a pair of bolts and wing nuts 49 adjustably received in a longitudinally extending slot 50 formed in the plate 46 for securing the plate 46 in longitudinally adjusted position with respect to the plate 45.

The lower end of the plate 46 is formed with a notch 51 adapted for engaging one of the rungs 7 of the lower ladder section 5.

Having thus described the invention, what I claim is:

1. A convertible ladder comprising a pair of ladder sections, one of said sections being of lesser length than the other section, each section including side rails converging toward one end, a pole member pivotally connected to the narrow end of the longer one of said sections, said pole member being pivotally connected to the narrow end of the shorter section, means for rigidly fastening said pole member and said shorter section in longitudinal alignment with each other and from relative pivotal movement in such alignment, a detachable brace for connecting said sections in an upstanding relative position with the sections flaring apart in a downward direction and with the pole member in the said longitudinal alignment with the shorter section and pivotally attached to the narrow end of the longer section, said ladder being reconvertible into a straight ladder by removing the detachable brace and swinging the rigidly connected shorter ladder section and the pole member at the pivotal connection between the pole member and the longer ladder section so that the longer and shorter ladder sections and the intermediate pole member are in longitudinal alignment with each other, the intermediate pole member and the adjacent end portions of the two ladder sections being provided with rung extensions at opposite sides thereof, and rail members secured intermediate their ends to the rung extensions of the ladder sections and of said intermediate pole member, the opposite ends of said rail members being secured to the opposite sides of the ladder sections.

2. A convertible ladder comprising a pair of ladder sections, one of said sections being of lesser length than the other section, each section including side rails converging toward one end, a pole member pivotally connected to the narrow end of the longer one of said sections, said pole member being pivotally connected to the narrow end of the shorter section, means for

rigidly fastening said pole member and said shorter section in longitudinal alignment with each other and from relative pivotal movement in such alignment, a detachable brace for connecting said sections in an upstanding relative position with the sections flaring apart in a downward direction and with the pole member in the said longitudinal alignment with the shorter section and pivotally attached to the narrow end of the longer section, said detachable brace 10 being foldable and longitudinally extensible, the ladder assembly being reconvertible into a straight ladder, the reconversion being effected by removing the detachable brace and swinging the rigidly connected shorter ladder section and pole member on the pivotal connection of the pole member with the longer ladder section so that the two ladder sections and intermediate pole member are in longitudinal alignment with each other, said pole member and the adjacent end portions of the ladder sections being 20 provided on opposite sides with foldable rung ex-

tensions, and detachable rail members attachable intermediate their ends to the outer ends of the foldable rung extensions on the end portions of the ladder sections and said intermediate pole member, the opposite ends of said rail members being attachable to the opposite sides of the ladder sections.
